DESCRIPTION

FIG. 1 is a perspective view of a universal hood and kit for laptop computer LCD screen in an open position;

FIG. 2 is another perspective view thereof in the compact storage position;

FIG. 3 is a front view thereof showing the joined sections;

FIG. 4 is a back view thereof;

FIG. 5 is a side view thereof;

FIG. 6 is a top view thereof;

FIG. 7 is a bottom view thereof;

FIG. 8 is an assembled perspective view thereof;

FIG. 9 is an exploded view thereof; and,

FIG. 10 is a single panel thereof.

The broken lines are shown in the views for illustrative purposes only and form no part of the claimed design.
